METHOD AND APPARATUS FOR MANUFACTURING AND ASSEMBLING CATHODE STARTING SHEETS FOR ELECTROLYSIS

Application filed May 23, 1929. Serial No. 365,537.

This invention relates to the manufacture of cathode sheets used in the electrolytic refining of copper. Such sheets have usually been flat sheets of electrolytic copper, but a recent important improvement is set forth in our patent granted December 15, 1931, numbered 1,836,368, wherein the sheets are straightened and stiffened by corrugation and have the loops for connecting them to the copper conducting rods united by a clinching method. Reference is made to that application for a more complete understanding of the precise preferred construction of the starting cathode.

The present invention provides for the more economical manufacture and assembling of such cathode sheets. The nature of the operations and the mechanisms for performing them will be made apparent as the description proceeds.

Referring to the accompanying drawings,

Figure 1 is a plan showing a suitable relative location of the various apparatus to be described.

Fig. 2 is an elevation partly in vertical section, showing the apparatus for feeding the electro-deposited copper sheets into the annealing furnace.

Fig. 3 is a similar elevation showing the means for removing the sheets, quenching them, and stacking them for reconveyance.

Fig. 4 is an elevation, partly in diagram, showing the means whereby the operations of feeding the sheets into the corrugating press, and feeding the completed sheets therefrom and stacking them on racks, are performed.

Fig. 5 is a fragmentary elevation showing the top and bottom of one of the completed sheets.

Fig. 6 is a vertical transverse section thereof on a larger scale.

Figs. 7 and 8 are enlargements of a portion of Fig. 4 showing two successive stages of the operation of applying loops.

Referring to Fig. 1, the sheets of electrolytic copper having been suitably stacked one on top of another and piled onto suitable cars or trams, these stacks being shown at *a*, *a*, are carried in pairs (or groups of three or

more) upon a table or support located at *b*, and from this are fed into an annealing furnace or oven *A* (preferably of the tunnel type), from which they are fed out and then immersed in water in a bosh *B* to cool them, after which they are superposed to form stacks *c* of which any convenient number located in, for example, the positions *c'*, may be accumulated and held in reserve ready for the next operation. Any one of these stacks *c* is then carried along tracks *d*, *e*, to either of the positions indicated at *f*, *f*, where they stand in convenient relation to corrugating presses *C*, *C*. Meanwhile the customary rods used with such sheets having been deposited in any suitable container *g*, are fed out therefrom and straightened in an apparatus located, for example, at *h*, and such portions of them as require to be polished are brightened by revolving wire brushes or wheels located at *i*, the rods being fed along a track or way shown in dotted lines at *j*, and finally carried to a feeder *k*, whereby the rods are carried to whichever of the presses *C*, *C*, is in operation; or if both are working, then alternately to first one end and then the other.

The operations performed by the presses will be later described. From the presses the completed sheets are carried out by a suitable feeding apparatus which then turns them from a horizontal into a vertical position, and feeds them successively onto carrying racks *D*, *D*. The completed sheets hung on these racks are lettered *l*, *l*. The carriers *D*, *D*, may then be trammed over tracks *m* leading to the part of the works where the electrodeposition to form electrolytic copper is performed.

Referring now to Fig. 2, the stack *a* is carried on a platform *n* transported on a car *E*, and is lifted by any suitable means, such as a hydraulic ram *F*, to bring the top sheet within range of a pneumatic sucker or other feeding device *p*. As the stack diminishes in height, it will be gradually fed up by the ram. The lifter *p* may be any known construction of pneumatic suction device operated, for example, by a reciprocating piston within a cylinder *q* and carried on a car *r* rolling on a

trolley track *s*. In operation the feeder *p* descends, picks up the top sheet from the stack, ascends, and then by the movement of the car *r* along the track *s*, brings the sheet to the position, shown in dotted lines, over the table or support *b*, whereupon the pneumatic suction ceases and the sheet is dropped onto this table. The feeder *p* then returns and repeats its operation, bringing a second sheet and dropping it on the first. The pair of sheets thus superposed are then fed into the annealing furnace *A*. This furnace, being preferably of the continuous tunnel type, has one or more endless chains 10 carried around sprockets 11, 11, and traveling through the muffle chamber *A'* of the furnace, the chains being provided at suitable intervals with pusher pawls 12 for pushing along the pairs of sheets. The sheets are first fed into the furnace by means of a feeder *u* carried on a carriage *v* which may roll along the same track *s*, and reciprocates at timed intervals, being provided with feeding toes which engage behind the successive pairs of sheets and push the two sheets at a time into the furnace, from which point they are fed along in succession with other pairs through the furnace by the chain feed. The feeders *u* work in slots in the table or support *b*, and the carriage *v* has its supporting members so far apart as to move freely beyond the outer edges of the sheets. The muffle or annealing furnace *A* is of any known or suitable construction. A stack *G* is shown with a connecting flue 13 controlled by a damper 14 for drawing vapors from the muffle up the stack.

Referring to Fig. 3, the other end of the furnace *A* is shown (the furnace being of any suitable length), and the same feed chain 10 appears in this figure, carried at this end on sprockets 15, 15. The chain is fed by any suitable driving mechanism, and either continuously or intermittently. During their progress through the furnace the pairs of sheets are suitably heated according to the usual annealing process. They are fed out of the furnace by feeders *H*, *H'*, each consisting of a car 16 rolling on a track 17 and carrying arms 18 which at their advancing ends have drop dogs 19 pivoted to them, which are adapted to slide freely over the tops of the sheets and drop down behind them during the movement to the left of the feeders; and during their movement to the right in Fig. 3 the dogs push the sheets along. The feeders *H*, *H'*, may be connected together and driven as one, or they may be separately reciprocated, as desired. The essential operation is that the feeder *H* feeds the sheets off from the chains 10 and out of the furnace, and to the position shown at 20, where they are above the bosh or cooling tank *B*. At the next stroke the feeder *H'* slides the sheets from the position 20 to position 21, where they are over the stack *c*.

Between the two successive feeding operations the pair of sheets in position 20 is plunged down into the water in the bosh, as, for example, to the position shown in dotted lines at 22. In position 20 they are received on a grating of any convenient kind, and this grating is itself plunged down, carrying the sheets with it into the water bath. To insure that the sheets shall promptly go under water, a push device (not shown) is provided, which may conveniently be formed as a series of pins.

In position 21 the sheets are first received on any suitable support and then this support is withdrawn abruptly so as to drop the sheets bodily onto the stack *C*. For falling onto this stack they are suitably guided, in order to form a straight stack, by any suitable gauging devices such, for example, as is shown at 23; like devices being provided on all four sides of the stack if desired.

The stack is thus piled on a platform 24 which is carried on a car 25 running on suitable tracks, and this car then may be run to carry the platform 24 into any of the positions shown at *c'* in Fig. 1, and eventually the stacks will be carried to either of the positions shown at *f* in Fig. 1.

Referring now to Fig. 4, the same car 25 is here shown, and the same platform 24. On arriving in this position *f*, a hydraulic ram *J* (or any other suitable lifter) rises up through an opening in the car body and lifts the platform 24, so that the top of the stack is brought up within convenient reach of another suction feed *w* which in its construction is essentially similar to that of the suction feed *p* of Fig. 2. It has a similar cylinder *q'*, but in this instance is not mounted on a car. In operation, this suction feed descends upon the stack, engages the top sheet, and lifts it to the position shown, holding it there while a rolling platform or car *K* having wheels traveling on a track *x*, rolls under the elevated sheet, whereupon the suction is released and the sheet is dropped onto the platform *K*. Then by any suitable automatic mechanism this platform is rolled along on its track to bring the sheet into the press *C*. This press is of any usual construction of corrugating press and may be operated either mechanically or hydraulically. As here shown, the bed 30 is movable and the head or platen 31 is immovable. On the bed is carried the lower die 32, while the upper die 33 is fastened beneath the head 31. These dies have reciprocal faces to impart the necessary corrugations to the sheet as it is squeezed between them. At the instant when the sheet is fed into the press, the bed 30 is lowered enough to afford the sheet free passage over the lower die. Or if the bed is immovable, the carriage is located to carry the sheet at a level suitably above the top of the lower die. The sheet is located in the press by any suitable gauges 130

(not shown) and is held against displacement by such gauges or by any suitable stops of well-known character. While the sheet is thus located, and before the upper die descends, the supporting bar for the sheet is fed into place and the suspension loops are applied, as will now be described.

Referring to Figs. 5 and 6, the sheet is lettered L, and its rod is M, the connecting loops 10 being lettered N, N. These loops are of copper, which are folded closely around the rod.

The rods, having been fed from their hopper g through apparatus h, i, k (Fig. 1), are pushed endwise by the feeder k to a position 15 35 (Fig. 4) above the entering side of the press, and then are carried down successively by a feeding mechanism 36 until finally, after the sheet has been fed into place in the press, one of the rods is brought down to position 20 40, where it is in the horizontal plane of the sheet and directly in front of it. In this position the two strips of copper to form the loops N, N, are fed into place against the rod and partly wrapped around it. These strips are 25 thus fed into a vertical plane, as shown at 39, and while the rod is held fast at its ends the strips are bent around the top and bottom sides of the rod in the manner shown in Fig. 7. This bending may be variously accomplished, 30 the means shown consisting of a plunger 41 which approaches the rod from the position shown at 41 in Fig. 4 and, encountering the strip, bends its upper and lower halves into horizontal positions against the top and bot-

35 tom faces of the rod, as shown in Fig. 7. The plungers 41 are then moved forward with the rod until the latter is brought to the position 50 in Fig. 4. Thus the two ends of the strips to constitute the loops are brought above and 40 below the plate L, and are then moved into contact with the plate by vertically-moving pressers 51, 52, as shown in Fig. 8. While thus held, the loop ends are in correct register with the clinching punches 37, which then de- 45 scend and penetrate through the three thicknesses of copper formed by the loop and sheet, so that the upper thicknesses are carried down through the lower ones and turned outward and pressed or clinched down firmly into 50 place, so as to bind the three layers of copper intimately together. The clinched joints thus formed are shown clearly in Figs. 5 and 6, at 38. The precise construction of punches or similar clinching means for accomplishing 55 this cutting and clinching of the metal preferably at a single stroke, forms no necessary part of the present invention, but will be made the subject of a separate application for patent. The punches 37 may conveniently be carried on the platen 31, or they might be otherwise mounted. If on the platen, the first 60 upward movement of the bed 30 causes the punches 37 to penetrate the metal and perform their function, and ultimately, as the dies 32, 33, come together and squeeze the

sheet between them, they impress the corrugations upon it.

The press may have the bed 30 fixed and the platen 31 movable, if preferred; or both may move.

At any time after the punches 37 begin to operate, or while the sheet is held between the dies, the folder 41 may recede, since the bar in position 50 is now securely attached to the sheet. The pressers 51, 52, also separate, so that as the dies 32, 33, move apart, the cathode sheet L is released and may be fed out from the press. The folders 41, after freeing themselves from the rod and loops, require to be moved out of the way of the carriage K, for which purpose they may be dropped to the position shown in dotted lines at 41' in Fig. 4.

The out-feeding of the finished cathode sheet is preferably performed by a movement 85 in the same direction as the in-feed, and whereby it is carried out to the right in Fig. 4. For this, of course, the stops or gauges which originally located it are made to move out of the way. The feeding out is performed 90 by any suitable grippers which seize the sheet and move it out, transferring it first to the horizontal position shown at 42. The same feeding mechanism preferably then swings the sheet from the horizontal plane into a 95 vertical plane, passing through the transitory positions indicated by dotted lines at 43 and 44 and bringing it to the vertical plane shown at 45.

The sheets are thus successively brought 100 into line with the racks on the rack cars D, D (Fig. 1), and the final movement of the feed deposits the sheet between two racks, with the projecting ends of the rod M over the upper edges of these racks, and leaves the 105 sheet there suspended by the rod.

The sheets require to be put into the racks with their rods alternately reversed. For this purpose the rods are reversed in the apparatus shown at g, h, or k (Fig. 1), and at 110 any convenient location, so that every alternate rod has its twisted end at the opposite side. The rods retain these relative locations during the successive operations, and consequently as they are successively fed to the position 45 in Fig. 4, they are presented onto the racks 46 in the proper alternated relations, so that as each rack is filled it carries the prescribed number and succession of cathode sheets in proper relation for being transported 115 to the electrolytic tanks.

The entire series of operations thus described are capable of being performed wholly by mechanical means and without any necessity of handling or manipulating the sheets 125 in any way other than directing the proper travel of the cars from place to place.

While it is preferable to superpose the sheets in pairs (or groups of three or more) for carrying them through the annealing fur-

nace, yet it is within the invention to carry the sheets through singly instead. Carrying them in pairs (or groups), however, is preferable, as it increases the capacity with a given length of furnace and duration of heating.

We claim as our invention:

1. The described mode of manufacturing cathode sheets of electrolytic copper, comprising (1) feeding successive sheets from a stack; (2) entering such sheets into an elongated muffle furnace; (3) carrying such sheets through such furnace, whereby they are heated to a suitable temperature; (4) feeding such sheets out of said furnace; (5) plunging the sheets into a bosh for cooling them; (6) stacking the sheets and transporting them to a press; (7) feeding the sheets from such stack into the press; (8) simultaneously feeding rods and loops to their prescribed relation with the successive sheets; (9) wrapping the loops around the rod and holding them with their ends embracing the sheet; (10) punching through the superposed layers of copper and clinching them together to unite the loops and rod to the sheet; (11) squeezing the sheet between the members of the press; (12) feeding the completed sheet out of the press, and (13) turning the sheet into a vertical plane and depositing it in a carrying rack with the projecting ends of the rod resting on the rack.

2. The described succession of apparatus, comprising a muffle furnace adapted for heating the sheets to proper temperature for annealing, means for feeding successive sheets from a stack, means for feeding the sheets into said furnace, means for propelling such sheets through the furnace, means for feeding the sheets out of said furnace, a bosh, means for plunging the sheets into the water of said bosh to cool them, means for stacking the sheets so that they may be transported; a press for squeezing the sheets, means for feeding the sheets from said last-named stack to the press, means for feeding rods successively into relation with the sheets, means for feeding pairs of copper strips to the rods, means for bending such strips into loops around the rod and holding them in prescribed relation with the sheet, means for clinching together the superposed layers of copper to firmly attach the loops and rod to the sheet, means for feeding the completed sheets from the press, and means for turning them into a vertical plane and for delivering them onto a rack.

3. The described mode of handling sheets of electrolytic copper for the manufacture of cathode sheets comprising (1) feeding successive sheets from a stack, (2) entering such sheets into an elongated muffle furnace, (3) carrying such sheets through such furnace whereby they are heated to a suitable temperature, (4) feeding such sheets out of said

furnace, (5) plunging the sheets into a bosh for cooling them, and (6) stacking the sheets one upon another and transporting them away from said bosh.

4. The described mode of manufacturing cathode sheets of electrolytic copper comprising the successive operations of feeding the copper sheets to a stamping press, simultaneously feeding rods and loops to prescribed relation with each of the successive sheets, wrapping the loops around the rods and holding them with their ends embracing the sheet, punching through the superposed layers of copper loops and sheet and clinching them together to unite the loops and rod to the sheet, squeezing the sheet between the members of the press, and feeding the completed sheet out of the press.

5. The described mode of handling cathode sheets of electrolytic copper from a stamping press, said sheets including an attached suspension rod, comprising feeding the completed sheet horizontally out of the press, turning the sheet into a vertical plane, and depositing it in a carrying rack with the projecting ends of the rod resting on the rack.

6. As a sub-process in the described mode of manufacturing cathode sheets of electrolytic copper, the successive steps of feeding the sheets singly from a stack, depositing such sheets on a support until a plurality of sheets are superposed thereon, and then feeding such plurality of sheets together into and through the furnace.

7. The described apparatus comprising a muffle furnace, means for carrying sheets through such furnace, means for feeding successive sheets into said furnace, means for feeding the sheets out of the furnace, a bosh, means for plunging the sheets into the water of said bosh to cool them, and means for stacking the sheets so that they may be transported.

8. The apparatus of claim 7 further comprising means for feeding sheets individually from a stack, means for depositing them upon a support until a desired plurality of sheets are superposed on such support, and means for feeding such superposed sheets together into and through said furnace.

9. The described apparatus comprising a press for squeezing the copper sheets, means for feeding the sheets individually to said press, means for feeding rods successively into relation with the sheets, means for feeding pairs of copper strips to the rods, means for bending such strips into loops around the rod and holding them in prescribed relation with the sheet, and means for clinching together the superposed layers of copper to firmly attach the loops and rod to the sheet.

In witness whereof, we have hereunto signed our names.

WM. F. EPPENSTEINER.

WILLIAM F. EPPENSTEINER.
